(57) CLAIM

The ornamental design for a textile sheet with camouflage pattern as shown and described.

DESCRIPTION

The file of this patent contains at least one drawing executed in color. Copies of this patent with color drawing will be provided by the Office upon request and payment of the necessary fee.

FIG. 1 is a plan view of a textile sheet with camouflage pattern according to the first embodiment of our new design; and,

FIG. 2 is a plan view of a textile sheet with camouflage pattern according to the second embodiment of our new design.

The broken lines surrounding each figure define the bounds of the claimed design and form no part thereof.
